CROQUET RACK

Roman V. Rutkowski, South Bend, Ind., assignor to South Bend Toy Manufacturing Co., Inc., South Bend, Ind.

Application March 3, 1958, Serial No. 49,867

Term of patent 7 years

(Cl. D14—3)

Fig. 1 is a side elevation of a croquet rack showing my new design.

Fig. 2 is a front elevation thereof;

Fig. 3 is a top plan view; and

Fig. 4 is a perspective view a mallet, stake and portions of two balls being shown in dashed lines for purposes of illustration only.

I claim:

The ornamental design for a croquet rack, as shown and described.
